(57) **CLAIM**

We claim the ornamental design for a hot air corn popper, as shown and described.

DESCRIPTION

FIG. 1 is a top, right perspective view of a hot air corn popper of the present invention.

FIG. 2 is a front view of the hot air corn popper depicted in FIG. 1.

FIG. 3 is a right, side view of the hot air corn popper depicted in FIG. 1.

FIG. 4 is a rear view of the hot air corn popper depicted in FIG. 1.

FIG. 5 is a left, side view of the hot air corn popper depicted in FIG. 1.

FIG. 6 is a top view of the hot air corn popper depicted in FIG. 1.

FIG. 7 is a bottom view of the hot air corn popper depicted in FIG. 1.

FIG. 8 is a bottom, right perspective view of the hot air corn popper depicted in FIG. 1; and,

FIG. 9 is a top, right perspective view of the hot air corn popper depicted in FIG. 1 with a removable lid portion illustrated in a removed configuration to show aspects of the design that are not visible with the lid portion in place.

The broken lines in the drawings illustrate portions of the hot air corn popper that form no part of the claimed design and may depict environmental subject matter only.

1 Claim, 9 Drawing Sheets
